DESIGN FOR A CLOTHESPIN

Earl J. Lytle, Los Angeles, Calif.

Application January 17, 1944, Serial No. 112,254

Term of patent 7 years

(Cl. D17—6)

To all whom it may concern:

Be it known that I, Earl J. Lytle, a citizen of the United States, residing at Los Angeles, in the county of Los Angeles and State of California, have invented a new, original, and ornamental Design for Clothespins, of which the following is a specification, reference being had to the accompanying drawing, forming part thereof, in which

Figure 1 is a side elevation of the clothespin; Figure 2 is an elevation at right angles to Figure 1; and Figure 3 is a perspective view of the clothespin.

I claim:

The ornamental design for a clothespin, substantially as shown.

EARL J. LYITLE.
